UNITED STATES PATENT OFFICE.

CHARLES FLEISCHER AND AUGUST SCHLAK, OF BROOKLYN, NEW YORK, ASSIGNEES
TO JOHN F. MEYER, OF CHICAGO, ILLINOIS.

AMUSEMENT DEVICE.

Application filed April 12, 1926. Serial No. 101,244.

The object of this invention is to provide a device which will furnish pleasure and amusement and be interesting to all who operate it.

5 A further object of the invention is to provide a device of simple construction adapted for operation by the insertion of a coin or token to furnish pleasure and amusement to the operator and those associated 10 with him.

In the accompanying drawings illustrating the invention;

Fig. 1 is a perspective view of the device.

Fig. 2 is a transverse sectional view.

15 Fig. 3 is a back view of the coin chute plate, and

Fig. 4 is a detail enlarged sectional view.

Referring to the drawings 5 is a cabinet having a front 6 pivoted at 7 to the sides 20 of the cabinet and provided with a lock 8 for securing the front in closed position.

A plate 9 is made in the general shape of a horseshoe having on its back edge flanges 10, 11. This plate is fastened to the pivoted front of the cabinet on the outer side thereof, with the flanges 10 and 11 engaging said front. The flanges space the plate from the pivoted front of the cabinet to form a coin chute 12 which extends down 30 both legs of the horseshoe and across the curved top thereof connecting said legs. At the top of the horseshoe there is an extension 9' of the plate and the outside flange 10 is extended up on the back of this extension and formed into a plurality of loops 13, which project beyond the extension. These loops all converge to a narrow passageway 14 between the rib 10 extending up from one leg of the horseshoe to the rib 40 extending up from the other leg of the horseshoe and the extensions 10' of the rib 10 which form the loops 13 on the back of the extension 9' of the plate 9 space the extension from the front of the cabinet just

45 as the ribs 10 and 11 space the legs of the horseshoe plate from the front of the cabinet and thereby form coin chutes which communicate through the single passage 14 with the coin chutes at the back of the legs of the horseshoe plate. In fact, almost the entire back of the extension is formed into a coin chute except for parts of the flange 10' constituting partitions between the loops.

50 The coin chute plate is fastened in any suitable manner on the pivoted front of the

cabinet and the outer end portions of the loops 13 are backed by the cabinet front and are open at the front to receive a coin or token which is inserted flatwise and permitted to travel down through the neck 14 60 and down either leg of the horseshoe plate. An opening 15 is provided in the cabinet from behind one leg of the horseshoe near the bottom thereof and a deflector 16 is provided on this leg of the horseshoe plate and 65 is arranged to deflect a coin or token 17 into the cabinet, as indicated in Fig. 4. The coin chute extends to the bottom of the other leg of the horseshoe which is cut away at 18. The flange 10 terminates at or above this 70 cut away portion 18 and the flange 11 has a side extension 11' at the bottom of the leg which is turned upward to arrest a coin which travels down to the bottom of the leg. The cut-out 18 permits this coin to be 75 readily removed. In practicing the invention the plate is cut out in a suitable manner and at intervals as at 19 to disclose a coin traveling through the chute.

80 In practicing the invention we have designed the extended part of the coin chute plate, at the top of the horseshoe, something like a four leaf clover with the loops 13 constituting the four leaves and with 85 designations disposed opposite the respective loops such as "Marriage", "Love", "Success", "Travel". We have also applied the word "Yes" to the leg which carries the deflector 16 and "No" to the leg having the delivery cut-out 18. A coin inserted in any 90 one of the loops 13 will travel through the neck 14 and down either leg of the horseshoe. If the coin travels down the right leg of the horseshoe in Fig. 1, it will be deflected into the cabinet; if it travels down the 95 left leg, it will be delivered to the player at the cut-out 18. We provide studs 20 below the neck and a sharp projection 21 on the flange 11 below the neck and the studs 20, to deflect the coin to one leg or to the 100 other leg of the horseshoe. We have shown snake-like openings 19' in the legs to disclose the travel of the coin and we prefer to provide studs 22 on the legs to cause the coin to travel tortuously down the legs in a 105 path of travel corresponding substantially with the curvature of the opening, for at least a part of its travel.

110 The invention provides a source of pleasure and amusement to anyone who may

operate it and to those who may be observing the operation. The operator places his coin in one of the loops 13 with an implied question having relation to the word which 5 appears opposite said loop. If the coin travels down one leg and is discharged into the cabinet, his question is answered affirmatively; if it travels down the other leg and is delivered to him at the cut-out 18, his 10 question is answered negatively. This creates interest and produces fun and amusement for those who may be observing the machine as well as to the one who is operating it.

15 We have described the device as operated by a coin or a token and we wish it to be understood that the token may be of any form capable of operation in the device, or of any form for which the device 20 may be adapted.

We are aware that changes in the form, construction and arrangement of parts of the invention may be made without departing from the spirit or sacrificing the advantages thereof and we reserve the right to 25 make all such changes as fairly fall within the scope of the following claims.

We claim:

1. The combination of a cabinet, a plate 30 in the form of a horseshoe secured to the front of the cabinet and having edge flanges spacing the plate from the cabinet to form a token chute between the back of the plate and the front of the cabinet, and means for 35 depositing a token in the chute at the top of the horseshoe to travel down either leg thereof.

2. The combination of a cabinet, a plate 40 in the form of a horseshoe secured to the front of the cabinet and having a token chute between itself and the front of the cabinet, an extension at the top of the plate, the token chute behind the horseshoe being continued behind said extension, a plurality 45 of loops projecting beyond the extension and communicating with the token chute at the back of the extension, said loops being open at the front to receive a token.

3. The combination of a cabinet, a plate

in the form of a horseshoe secured to the 50 front of the cabinet and having edge flanges spacing the plate from the front of the cabinet to form a token chute therebetween, an extension at the top of the plate, flanges on said extension forming a token chute at 55 the back thereof, the token chute at the back of the extension being connected with the token chute at the back of the horseshoe by a narrow neck, and loops projecting beyond the edge of the extension and closed at 60 the back by the front of the cabinet and adapted to receive a token to travel through the chute at the back of the extension and through the chute at the back of one of the legs of the horseshoe.

4. The combination of a cabinet, a plate 65 in the form of a horseshoe secured to the cabinet and having edge flanges spacing the plate from the front of the cabinet to form a token chute therebetween, studs spaced apart at the top of said token chute, and a projection located below said studs to direct a token into the chute at the back of one leg or the other of the horseshoe, and means for 70 guiding a token to said chute.

5. The combination of a cabinet, a plate 75 in the form of a horseshoe secured to the front of the cabinet and having edge flanges spacing the plate from the cabinet to form a token chute therebetween, said cabinet having an opening in the front thereof, and a deflector on the back of one leg of the plate for deflecting a token from the chute through 80 the opening into the cabinet.

6. The combination of a cabinet, a plate 85 in the form of a horseshoe secured to the front of the cabinet and having edge flanges spacing the plate from the front of the cabinet to form a token chute therebetween, one leg of the plate being cut away at the 90 bottom thereof, the outside flange on said leg terminating above said cut away portion, and the bottom flange on said leg being extended beyond said cut away portion and turned upward to arrest the token.

CHARLES FLEISCHER.
AUGUST SCHLAK.
